PAPER DISPENSER

Frank L. Broeren, Menasha, Wis., assignor to
 Marathon Paper Mills Company, Rothschild,
 Wis., a corporation of Wisconsin

Application April 11, 1934, Serial No. 720,026

1 Claim. (Cl. 312—62)

An object of this invention is to provide an improved and simplified form of device for dispensing interfolded paper sheets, particularly waxed paper sheets.

5 This and other objects, as will hereinafter appear, are accomplished by this invention which is fully described in the following specification and shown in the accompanying drawing, in which—

Figure 1 is a perspective view of a dispenser embodying this invention;

10 Fig. 2 is an enlarged side elevation of the edges of interfolded sheets; and

Fig. 3 is an enlarged transverse vertical section through the dispenser.

15 This invention relates particularly to a device for dispensing wax paper for use in delicatessens, grocery stores, meat markets, or the like, for wrapping meats, cheese, etc. Because of the slippery nature of the wax paper the sheets have a tendency to slide over each other much more readily, and provision must be made for this as will later appear.

20 The device consists essentially of a container 10, preferably rectangular in form, having a hinged cover 10^a and a front 11 having a transverse horizontal slot 12. Behind the front are located two members 13, 14 which terminate at the horizontal slot 12, the outer surfaces of which are provided with raised portions 13^a, 14^a, both 25 of said members sloping generally toward the slot 12.

25 The sheets to be dispensed are interfolded, as shown in Fig. 2, and placed in stacks. Thus the sheet A is in the form of a V with the bottom of the V at the bottom of the sheet, the next sheet B being similarly formed but inverted so that the bottom of the V is now at the top of the sheet, the sheet B enclosing the trailing end of the sheet A and the forward end of the next sheet A'. The 30 sheets A and B continue to alternate in this same manner.

35 When placed in the dispenser the sheets rest upon a bottom 15 which is preferably inclined toward the front and are pressed against the front, as will later be described. On inserting the sheets the forward end of the sheet A is passed through the slot 12, as shown in Fig. 3. The sheets are pressed toward the front preferably by means of a plate 16 to which is attached two lugs 40 17, between which are journaled a roller 18 which is preferably placed near the center of the plate 16 and which rolls on the inclined bottom 15. Thus the weight of the roller which is quite heavy tends to force the plate 16 constantly toward the front of the dispenser compressing the stack of paper sheets against the surfaces 13^a, 14^a, but leaving the centers of these sheets relatively free to flex.

45 In order to insure the generally upright position of the plate 16, a stop 19 is secured thereto

which has a lower corner 19^a which will engage the bottom 15 if the plate is rocked backward about the roller. On the other hand, if the plate has a tendency to rock forward, the lower edge 16^a of the plate will engage the bottom and the 5 weight of the roller will tend to return the plate to its normal vertical position.

Thus with the free edge of the first sheet as A extending through the slot 12, the operator grasping this forward edge can pull the sheet through 10 the slot and it will draw the downwardly extending forward edge of the next interfolded sheet B through the slot, so that when the sheet A (Fig. 3) is removed from the dispenser the next sheet B 15 will have a downwardly extending edge, as shown in dotted lines, which in turn can be pulled to remove it from the slot, and it in turn will draw the next forward edge of a sheet A through the slot.

Owing to the slippery nature of the wax paper 20 a pull on the forward edge of the sheet A tends to lift the trailing end of the sheet A and the sheet B. To overcome this tendency I have placed stops 20, preferably one at each side of the dispenser, which overlie the stack of paper sheets 25 and which extend a short distance thereover so as to prevent any tendency of the sheets to rise as the sheets A are withdrawn.

A hook 21 is attached to the upper portion of 30 the plate 16 whereby the plate may be hung conveniently on the edge of the rear wall of the container out of the way in order to facilitate the refilling of the container with sheets to be dispensed.

While I have shown and described but a single 35 embodiment of my invention, it is to be understood that it is capable of many modifications. Changes, therefore, in the construction and arrangement may be made which do not depart from the spirit and scope of the invention as disclosed 40 in the appended claim.

I claim:

A dispenser for stacked sheets of paper comprising a container of boxlike formation having front and back walls and side walls, the front wall 45 having a transversely extending slot formed therein for the withdrawal of sheets singly and adjacent which said sheets are held in facewise relation, an inclined floor adapted to have the sheets stacked thereon, a follower plate normally standing vertically, a roller behind the follower plate and journaled at its ends thereto in position to normally roll with its full free surface upon the inclined floor and hold the follower plate in elevated relation thereto and permit the follower 50 plate to tilt in order to adapt its surface to the stack of sheets, and means associated with the follower plate for limiting the extent of said tilting.

FRANK L. BROEREN. 60
